Modern Curtain Co. Inc., Boston, Mass., a cor-
poration of Massachusetts

Application January 27, 1938, Serial No. 74,604

Term of patent 14 years

To all whom it may concern:

Be it known that I, Frederick A. Baird, a citizen of the United States, residing at Wilmette, in the county of Cook and State of Illinois, have invented a new, original, and ornamental Design for Curtain, of which the following is a specification, reference being had to the accompanying drawing, forming part thereof, wherein the figure is a front elevation of a curtain showing my new design.

My design embodies a two-section, tie-back curtain characterized by a cascade or vertically

sinuous configuration below the tie-backs and adjacent to the upper margin of the space between the sections, the lower margins of said space being defined by substantially straight section portions leading upwardly to the lower ends of said cascades, resulting in the appearance shown.

I claim:

The ornamental design for a curtain substantially as shown and described.

FREDERICK A. BAIRD.
